ber 6, 1941, Serial No. 409,863

6 Claims. (Cl. 200—52)

This invention relates to a restoring vibration-actuated switch.

It is the object of this invention to provide a switch which will be initially operated, preferably released, by excessive vibration of the device to which the switch is attached, the release of the switch serving to effect an electric circuit to cause the cessation of the excessive vibration.

Another object of the invention is to provide such a switch with a heat-responsive element adapted to force the switch into a reset condition after a predetermined lapse of time, the tripping of the switch and the resetting being repeated time after time, so long as excessive vibration recurs after the resetting of the switch.

The subject matter of this application is a division of my application for United States Letters Patent Serial No. 137,662, filed April 19, 1937, and entitled "Cleaning Machines."

My invention is illustrated in the accompanying side-elevation drawing in which the switch case is shown in section and in which an external electric circuit, including a source of current and a magnetic device, is diagrammatically illustrated.

The invention is preferably enclosed in a box or container 1 having a backplate 2 suitably attached to a machine, not shown, the excessive left and right vibration of which is to be checked. Mounted on the backplate 2 is a support 3 upon which a pendulum or inertia member 4 is pivoted at 5 to swing through an arc limited by the shoulders 6 and 7 at the ends of a slot through the lower wall of the container 1. The upper arm of the pendulum 4 is provided with a forwardly-extending offset portion 9 which is arcuately formed about the pivot point 5, the lower face of the forwardly-extending portion 9 being substantially perpendicular to the plane in which the pendulum swings. A contact spring 10, having an end 11 arcuately formed about the pendulum pivot point 5, normally engages the under side of the forwardly-extending offset portion 9 to hold the contacts 14 and 15 in engagement with one another.

Mounted above the contact spring 10 is a bimetal strip 16 having an end 17 adapted to move into operative engagement with the contact spring 10 when the bimetal strip 16 is heated for a predetermined length of time by the heating coil 18, which lies near but preferably out of contact with the bimetal strip 16. The heating coil 18 is of high resistance and is connected, in parallel, with the contacts 14 and 15 so that, in normal condition, current from the source 20

and through the electromagnet 21 is shunted away from the heating coil 18 by the low-resistance path through the contacts 14 and 15. The resistance of the electromagnet 21 is low compared with the resistance of the heating element 18 so that the amount of current passing through the electromagnet 21, when the contacts 14 and 15 are opened, is insufficient to energize the electromagnet 21 to an operative extent, but is sufficient to heat the high-resistance heating element 18 to such an extent that it causes the downward deflection of the bimetal strip 16, the engagement of the part 17 with the contact spring 10 and the forcing of the end 11 of the contact spring 10 past the projecting point of the forwardly-extending offset portion 9 of the pendulum lever by moving the pendulum lever in a counterclockwise direction about its pivot point 5.

In operation, the backplate 2 will be attached to a machine or structure adapted to be started or to have its speed increased by the energization of the electromagnet 21. If a condition within the machine to which the backplate 2 is attached is such that excessive vibration to the right and left takes place, the pendulum 4 will swing until the end 11 of contact spring 10 is released from the point of the forwardly-extending offset portion 9, thus breaking the operating circuit of the electromagnet 21 and permitting current to pass through the heating element 18 sufficiently gradually to heat the bimetal strip 16. The space between the heating element 18 and the bimetal strip 16 may be adjusted to provide any desired lapse of time for the machine to which the backplate 2 is attached to come to rest or to decrease its speed to a point where the out-of-balance condition, which was the cause of vibration, has been rectified. After the requisite predetermined time has elapsed, the bimetal strip 16 bends downwardly and pushes the end 11 of contact spring 10 past the point of the forwardly-extending offset portion 9, resetting the switch, closing the contacts 14 and 15, shunting the heating coil 18 and magnetizing the electromagnet 21 to again start or increase the speed of the machine to which the backplate 2 is attached.

During the restarting period, the bimetal strip 16 cools sufficiently that if the machine is still or again in unbalanced condition, so that vibration again occurs, the end 17 and the contact spring 10 will have had time to become separated, so that contacts 14 and 15 may again open the operative circuit of the electromagnet 21. Al-

though the interval between the opening of contacts 14 and 15 and their reclosing will be shorter for successive operations than for the first operation because of the residual heat in the bimetal strip 16, the time required to bring the machine to which the backplate 2 is attached from its stop condition or its slow-speed condition to the condition of possible vibration must be sufficient to permit of sufficient cooling of the bimetal strip 16 to permit the contacts 14 and 15 to separate under conditions of excessive vibration.

While I have shown and described my invention with respect to specific details of construction, it is to be understood that modifications may be made within the skill of the art without departing from the spirit or scope of my invention.

What I claim is:

1. A machine control comprising a switch having contacts yieldingly urged apart, means for holding said contacts together, inertia means for releasing said holding means in case of excessive vibration, and heat-responsive means actuated upon release of said holding means for automatically reengaging said holding means after a time interval.

2. A machine control comprising a switch having contacts yieldingly urged apart, means for holding said contacts together, inertia means for releasing said holding means in case of excessive vibration, a circuit energized by the release of said holding means, and heat-responsive means operated by the energizing of said circuit for re-engaging said holding means.

3. A machine control comprising a switch having contacts yieldingly urged apart, means for holding said contacts together, inertia means for releasing said holding means in case of excessive vibration, a circuit energized by the release of said holding means, a heat-generating device energized by said circuit when energized, and a thermally-responsive member deflected by heat from said device to reengage said holding means.

4. A machine control comprising a pair of normally-closed switch spring contacts, a pivotally supported inertia member, a pair of surfaces in normal engagement with one another, one of said surfaces being movable with one of said switch spring contacts and the other of said surfaces being movable with said inertia member,

the surface movable with the inertia member being substantially arcuate about the pivotal support for the inertia member, whereby the movement of the inertia member within predetermined limits does not cause movement of the associated switch spring contact, the said engaging surfaces of the inertia member and the switch spring contact being separable by excessive oscillation of the inertia member about its pivotal support, whereby the switch spring contacts become separated, and a heat-operated member adapted to engage the said movable switch spring contact member to force the said surfaces into reengagement with one another after the excessive oscillation of the inertia member has subsided.

5. A machine control comprising a pair of contacts normally biased away from one another, an inertia-controlled latch normally holding said contacts together against the said normal bias, a bimetal strip having a portion for operative engagement with one of said contact members for pressing said contact members together in opposition to the said bias, the movement of said bimetal strip in forcing said contacts together serving simultaneously to reset said inertia-controlled latch.

6. For use upon a vibrating machine and in series with a source of current and an electromagnetic device the actuation of which may cause the vibration of said machine, a machine control comprising a pair of switch contacts, one of said contacts being normally under tension tending to separate said contacts, a pair of latch members normally holding said contacts in engagement with one another, a pivoted inertia member connected with one of said latch members for separating the latch members upon excessive oscillation of the inertia member, a bimetallic heat-controlled member positioned to engage one of said latch members to press the latch members into related position upon the application of heat to said heat-controlled member, an electric heating element connected in parallel with said pair of contacts and normally shunted thereby, the resistance of said heating element being high relative to the resistance across said contacts when the latter are closed.
